UNITED STATES PATENT OFFICE.

WILLIAM T. MURPHY, OF NEW YORK, N. Y.

DESIGN FOR A BOTTLE.

SPECIFICATION forming part of Design No. 20,469, dated January 6, 1891.

Application filed December 13, 1890. Serial No. 374,631. Term of patent 3½ years.

To all whom it may concern:

Be it known that I, WILLIAM T. MURPHY, a citizen of the United States, residing in the city of New York, in the county and State of New York, have invented and produced a new and original Design for a Bottle, of which the following is a specification, reference being had to the accompanying photograph, which represents a perspective view of a bottle embodying the design.

The feature of the design is a figure simulating an oyster-shell, one end whereof is given a cylindrical neck-like outline.

I claim—

A design for a bottle, substantially as herein shown and described.

WILLIAM T. MURPHY.
